UNITED STATES PATENT OFFICE

1,996,645

DUPLICATING STAMP

George J. Helfrich, Cincinnati, Ohio

Application April 11, 1933, Serial No. 665,541

6 Claims. (Cl. 101—131)

My invention relates to duplicating stamps of the type operable by hand generally through a rocking motion.

The principal object of the present invention is to provide a simple, inexpensive and efficient duplicating stamp.

A further object of the invention is to provide a stamp of the character mentioned in which the duplicating means proper consists of a gelatinous surface of the hectograph type.

Another object of the invention is to provide in a stamp of the type mentioned means wherein a gelatinous duplicating surface may be readily interchangeable with another similar surface, so that when worn or for any other reason not immediately available, it may be replaced by a new duplicating surface ready for immediate operation.

A still further object of the invention is to provide in connection with a stamp of the type mentioned simple and efficient allocating means whereby impressions produced by said stamp may be accurately placed with respect to the sheets upon which successive impressions are made so that the several copies may be of uniform justification and appearance.

Further objects of my invention will appear from the following detailed description thereof:

In the drawing:

30 Figure 1 is a section of a duplicating stamp and allocating member or pan constructed in accordance with this invention taken on line 1—1 of Figure 2.

35 Figure 2 is a top view of the stamp and allocating pan.

Figure 3 is a side elevation of the stamp and pan indicating the means of operation.

The numeral 1 indicates a metal base plate of arcuate section. Centrally located in the base plate 1 is a socket 2 within which a pin 3 is rigidly secured. A short distance above the socket 2 the pin is provided with a collar 4, the free end of the pin extending upwardly beyond the collar and being threaded as shown at 5 to receive a handle 6 which screws on to said pin. Adapted to be mounted on the plate 1 is a spring plate 7 having upwardly and inwardly turned flanges 8—8 which are adapted to form grooves arranged freely to receive the edges of plate 1. Plate 1 while slightly curved is of less normal curvature than plate 1 so that the plates may be held rigidly together when assembled by means of the tension of plate 7, whereby its flanges are firmly pressed against the upper surfaces of plate 1 along its edges. Plate 1 is provided with a gelatinous

surface or face 9, the material used being preferably that employed in hectograph duplicating devices, the same being a material well known and in common use. Said gelatinous material is secured to plate 1 by any suitable adhesive as for instance shellac or glue, or may be molded on said plate.

The numeral 10 indicates a plate having a section 11 bent at right angles to its main portion, said section 11 terminating in an angularly disposed flange 12. Plate 10 is provided with a perforation adapted to fit over pin 5 and the extension 11 is of such height that when plate 10 rests on the collar 4, flange 12 abuts against the upper surface of plate 1. Plate 10 is provided with a lateral extension 13 having an upwardly inclined terminal edge 14. The numeral 15 indicates a plate adapted to fit the under side of extension 13 of plate 10 and to be secured thereto by any suitable means. Plate 15 has a downwardly extending portion 16 terminating in an angularly disposed flange 17 arranged to rest against the upper side of plate 1 on the opposite side of pin 3 from flange 12. Secured to the under side of plate 15 at the angle formed by the terminal edge 14 are spherical studs 18, said studs being arranged to cooperate with depressions in the allocating member or pan next to be described.

The numeral 19 indicates the base of a rectangular pan which has a rear wall 20 terminating in a horizontal section 21, and a supporting flange 22. The horizontal section 21 is provided with sockets or depressions 23 for the spherical studs 18. The pan is further provided with a short side wall 24, adjacent the rear wall 20 and extending forwardly from the left end thereof.

The use and operation of my new duplicating stamp and allocating means are as follows:

The plate 1, handle and connecting portions 40 being assembled as shown in Figures 1 and 3, plate 1 carrying a gelatinous face surface, is slipped on plate 1 by means of compressing plate 7 along the chord of its arc so that it corresponds substantially with the arc of plate 1. Plate 7 45 may then be slid easily into its proper position on plate 1. When so positioned, release of plate 7 will cause it to spring to its original shape causing the flanges 8—8 to engage firmly the upper surfaces of the edges of plate 1. Plate 7 with the gelatinous face is thereby fixedly secured in assembly with the other elements of the stamp. The gelatinous surface having been provided with the matter to be duplicated through the absorption by the gelatin of the printing ink in 50 55

the manner long familiar for the operation of the hectograph, the operation of duplication is performed as follows:

5 A stack of sheets or cards 25 is placed in the allocating member or pan with the rear edges of the sheets abutting against the rear wall and the left side edges abutting against the short wall 24; all of the sheets or cards are thus uniformly located in the pan. Proper placement of the 10 stamp is then effected by locating the spherical studs 18 in the depressions 23 of the pan. Successive copies are made merely by rocking the stamp forward into contact with the several sheets as presented, reallocation of the stamp 15 being effectually accomplished after each impression by the centering of the spherical studs in the depressions as will be apparent.

As will be understood the owner and operator 20 of a stamp constructed in accordance with this invention may be supplied with any number of spring plates with gelatinous surfaces needed to meet his normal requirements, such plates being inexpensive and readily interchangeable.

25 Having thus fully described my invention, what I claim as new and desire to secure by Letters Patent is:

1. A duplicating stamp of the character mentioned comprising an arcuate plate, means for the operation of said plate, a spring plate of less 30 curvature than said arcuate plate, flanges along edges of said spring plate forming channels into which the edges of said arcuate plate are adapted to slide longitudinally, and a gelatinous surface permanently secured to said spring plate.

35 2. A duplicating stamp of the character mentioned comprising a plate, a second plate removably secured to said plate, means for the operation of said plates, allocating means carried by said second plate, and a gelatinous surface 40 permanently secured to said first plate.

3. A duplicating stamp of the character men-

tioned comprising an arcuate plate, a second plate removably secured to said arcuate plate, means for the operation of said plates, allocating means carried by said second plate, a spring plate of less curvature than said arcuate plate, flanges along edges of said spring plate adapted to receive edges of said arcuate plate, and a gelatinous surface permanently secured to said spring plate. 5

4. A duplicating stamp of the character mentioned comprising a plate, a second plate removably secured to said plate, means for the operation of said plates, allocating means carried by said second plate, a gelatinous surface permanently secured to said first plate, a pan for holding sheets to be stamped, and allocating means carried by said pan arranged to cooperate with the allocating means on said stamp. 10

5. A duplicating stamp of the character mentioned comprising an arcuate plate, a second plate removably secured to said arcuate plate, means for the operation of said plates, allocating means carried by said second plate, a spring plate of less curvature than said arcuate plate, flanges along edges of said spring plate adapted to receive edges of said arcuate plate, a gelatinous surface permanently secured to said spring plate, a pan for holding sheets to be stamped, and allocating means carried by said pan arranged to cooperate with the allocating means 20 25 on said stamp.

6. In combination with a duplicating stamp, a pan for holding sheets to be stamped, said pan comprising a base, a rear wall, a short side wall at one end of said rear wall said rear and side 35 walls serving as rear and lateral stops for said sheets, a horizontal section formed with said rear wall, and allocating means carried by said horizontal section.

40
GEORGE J. HELFRICH.
